CONTACT STRUCTURE

John A. Herbst, Oradell, N. J., assignor to The
Teleregister Corporation, New York, N. Y., a
corporation of Delaware

Application June 19, 1937, Serial No. 149,237

5 Claims. (Cl. 200—166)

This invention relates to electrical structure particularly adapted for vibratory contacts of high speed instruments such as relays employed in telegraph systems, telephone systems, automatic stock quotation systems and the like.

Various attempts have been made heretofore to provide contacts for relays, interrupters and the like in which the formation of sparks or prolonged electric arcs between the contacts, which results in excessive erosion and burning of the contacts, is minimized or prevented, and various metals have been proposed, for example, platinum, alloys of platinum and iridium, tungsten carbide sintered with other metals acting as a binder for the tungsten carbide. Aside from the problem of reducing burning of the contacts, however, the problem of signal distortion due to contact bounce has been a serious one, particularly in high speed operating systems, for example, stock quotation systems. Any appreciable distortion of the signals in such systems tends to cause the stock quotation indicators, or other devices on which the quotations are displayed, to take incorrect settings, and the unfortunate results incident to the posting of a wrong stock price will readily be appreciated. Therefore, while it is highly desirable to prevent burning and pitting of the contacts thereby to obviate the necessity of unremitting attention and maintenance involving filing and burnishing of the contact faces, it is more important that correct, undistorted signals invariably will be transmitted or received by the relay contact structures employed in stock quotation transmitting, repeating and receiving stations.

An object of the present invention is the provision of suitable means for eliminating chatter and bounce of contacts, thereby to obviate the foregoing disadvantages.

Another object of the present invention is the provision of a simple and effective contact structure wherein a critical adjustment of the contacts is not required.

Another object is the provision of complementary contacts having surface characteristics and contact supporting structure such that the contacts will remain continuously in contact with each other after the contacts are first brought into mutual engagement.

A further object is the provision of resilient supporting means for relay contacts or the like, having substantially the same period of vibration, or frequency, whereby separation of the contacts is avoided during the transient period of vibra-

tion immediately following the closure of the contacts.

A still further object of the invention is the provision of a biasing field for a relay comprising two magnets so mounted that the flux of one magnet aids that of the other.

Still further objects will appear from a consideration of the description and drawings of a preferred embodiment of the invention, in which—

Fig. 1 is a plan view of a relay employing the invention.

Fig. 2 is a view in elevation partly broken away of the relay of Fig. 1.

Fig. 3 is an enlarged view in elevation of the relay of Figs. 1 and 2 more clearly showing the electrical contact structure.

Fig. 4 is a view partly broken away taken along the line 4—4 of Fig. 1.

Figs. 5 to 10 show the action of the contacts as the relay of Fig. 1 operates.

Referring first to Figs. 1, 2 and 3 there is shown thereon a relay having two permanent magnets 1 and 2 secured thereto by means of the screws 3 and 4 in such a manner that the north pole of one magnet is directly above the north pole of the other when the relay is in the position shown in Fig. 2. The ends of the magnets are connected together by the strips 5 and 6 of magnetic material which support the pole pieces 7 and 8. The armature 9 moves laterally within the coil 10 and is provided with a resilient member 12 secured thereto by any suitable means, such as for example, by welding, the member 12 supporting a contact 13 preferably composed of an alloy of tungsten carbide, the surface characteristics of which contact are hereinafter set forth in detail. The armature 9 is normally in the position shown on Fig. 1 resting against the pole piece 8 but separated therefrom by a small disc 14 preferably of non-magnetic material to prevent a sticking action between the armature and the pole piece with the relay in the unoperated position. A similar disc is provided to engage the pole piece 7 when the relay is oper-

ated. A resilient spring 15 secured by the screws 16 supports the contact 17 and is tensioned against the adjusting screw 18. The contacts 13 and 17 are preferably provided with somewhat rounded contact surfaces although the surface of either contact may be flat. The contact 17 is insulated from the frame 11 of the relay by the insulating washers 19 and is provided with a terminal 21 to which is attached the conductor 22. Secured

to the frame 11 is a conductor 23 and it will be understood that when the contacts 13 and 17 engage each other, a circuit is established by way of these contacts between the conductors 22 and 23 which terminate on slip connections or in any other suitable manner within the base 27 of the relay. The spring 15 has a resilient extension 24 supporting the contact, Fig. 4.

The limit of movement of the armature 9 is determined by the adjustment of the pole pieces 7 and 8, and the movement of the contact 13 is determined by the settings of the adjusting screws 25 and 18 and is such that the resilient member 12 normally rests against the adjusting screw 25, and when the relay is in the operated position the armature 9 rests against pole piece 7 and the contacts 13 and 17 are in engagement with each other. The pressure exerted by the contact 13 against the contact 17 may be varied at will, by means of the adjusting screw 18, in accordance with the current flowing through these contacts.

The operation of the relay will best be understood by reference to Figs. 5 to 10 of the drawings, in which Fig. 5 shows the relay armature in the unoperated state with the armature 9 resting against the pole piece 8 but separated therefrom by the disc 14. It will be understood that Figs. 5 to 10 are idealized for explanatory purposes, and are not to be taken as exact with respect to the extent of movement and flexure of the contact springs, but are intended to illustrate the principles involved. To more clearly illustrate the action of the contacts, the make spring 24 is shown in the same plane as the armature spring 11. As an impulse of the proper polarity is transmitted to the relay magnet coil, the armature 9 moves quickly toward the pole piece 7. The adjustment of the relay, however, is such that the contacts 13 and 17 engage each other before the armature comes into contact with the pole piece 7 as shown in Fig. 6. As the armature 14 continues its movement until it strikes the pole piece 7, the resilient armature member 12 is first flexed in the direction shown on Fig. 7 and the contact 13 moves relative to the contact 17. When the armature strikes the pole piece the armature contact continues to move in the direction of operation due to the inertia of motion stored up in it until the contacts assume the position shown in Fig. 8 and the contacts 13 and 17 have moved such that a second rubbing action between the contacts 13 and 17 has taken place, and the resilient spring 24 is flexed backward in the manner indicated. When the energy of inertia has been transferred from the armature contact to the make contact spring, the make contact spring 24 tends to restore thus transferring energy to the armature spring 12. When the energy has been stored in the armature spring, a third rubbing action of the surfaces of the contacts has resulted and the contacts are in the position shown in Fig. 9.

A preferred contact material employed in connection with the present invention is an alloy of finely divided tungsten carbide sintered with an auxiliary metal such as iron, cobalt, nickel or osmium acting as a binder for the tungsten carbide. Several of such alloys are disclosed in the patent to Louis Casper, No. 2,056,919, issued October 6, 1936. When contacts comprising such materials are closed, the heat generated by the current passing through the contacts melts some of the binder near the point of contact, thus releasing several particles of tungsten carbide. As

each particle is released it leaves a minute crater in the surface of the contact and thus causes the contact to have a rough surface during the life thereof. Therefore, when the two complementary contacts 13 and 17, composed of one of the above mentioned alloys of tungsten carbide, are closed, a frictional effect is obtained between the adjacent contact surfaces and, as hereinafter explained in detail, this frictional effect rapidly damps out the oscillations of the contact supporting springs.

The cycle of operations of Figs. 8 and 9 is repeated rapidly until all the energy has been dissipated at which time the contacts come to rest in the position shown in Fig. 10 with a slight flexure in the springs 12 and 24, and with the contacts 13 and 17 in substantial alignment and exerting pressure against each other.

The rate of flexing of the springs 12 and 24 tends to follow their natural periods of vibration, and if the natural periods or frequencies, of the two springs were identical the contacts would tend to remain in contact closing position without chatter or bounce throughout the period of vibration of the springs.

However, it is impracticable to manufacture spring assemblies whose natural frequencies or periods of vibration are identical, and when metallic contacts having smooth surfaces are employed, as has heretofore been the practice, the back and forth movement of the contacts is repeated many times for each operation of the armature and this continued movement or vibration of the contact springs produces an out of phase relation between the contacts, causing the contacts to momentarily separate and distort the signal and also produce a spark or arc at the contacts.

By employing tungsten carbide contacts having the surface characteristics herein described, and causing the frequencies of the contact supporting structures to be substantially the same, this oscillatory or vibratory condition of the contact springs is rapidly attenuated, and the contacts come to rest, after one or two such vibrations and before the phase difference in frequencies of the armature and make contact springs has increased sufficiently to produce a momentary separation of the contacts.

As the contact springs flex in the manner described above, they produce motion of the contacts relative to one another in a direction normal to the line of operation which produces a rubbing action and frictional effect between the faces of the contacts. Since the contact faces are rough, considerable energy is required to overcome the friction between the contacts, and this energy is absorbed from the oscillatory motion of the contact springs, thus rapidly attenuating their vibration and bringing them quickly to rest.

The armature 14 is maintained in positive engagement with the pole piece 7 during the attenuation period by means of the flux set up by dual magnets 1 and 2 acting upon the flux set up in the armature 9 by the current in the electromagnet 10, and this action of the dual magnets also assists in preventing contact bounce. This will be more clearly understood from the following consideration of the pull exerted on the armature 9 by the magnetic fields set up in the relay. Where X represents the value of flux which is normally set up because of the presence of the permanent magnets 1 and 2, and Y represents the flux set up by the current passing

through the electromagnet 10, the effective pull on the armature when the relay is energized may be determined generally by the expression

$$X^2 \pm 2XY + Y^2$$

5 The component of the total flux which is effective to actuate the armature 9 and to hold it in its actuated position is represented by the second term $2XY$. Therefore, by using dual magnets, 10 the value of X is large, and the product represented by the term $2XY$ is correspondingly large, which causes quick response of the armature and positive action in maintaining the armature in its actuated position. In other words, the force 15 which actuates the armature is proportional to the product of the permanent flux and the flux generated by the electromagnet 10, and since the flux set up by the dual magnets produces a very high flux density at the pole pieces, the strength 20 of which flux is a factor in the action of the relay, the relay not only has an improved and positive action, but the force tending to hold the contacts together is much greater for a given current, thereby tending to prevent vibration and 25 separation of the contacts when they are in circuit closing position. It will be understood that the sign plus or minus before the term $2XY$ is determined by the direction of the current flowing in the electromagnet 10, the armature 9 30 moving to circuit closing position in response to current of proper polarity.

While the invention has been described in detail with respect to a particular preferred example thereof which gives satisfactory results, it 35 will be understood by those skilled in the art after understanding the invention, that various changes, substitutions and modifications may be made without departing from the spirit and scope of the invention, and it is intended therefore 40 fore in the appended claims to cover all such changes and modifications. As heretofore stated, the contact material preferably is composed of or comprises an alloy of tungsten carbide, but obviously any other alloy or metallic substance 45 which will maintain a sufficiently rough surface to give the stated frictional effects, and which has the necessary electrical characteristics, may be employed.

What is claimed as new desired to be secured 50 by Letters Patent is:

1. An electrical switch structure comprising at least two complementary metallic contact members, mounting means whereby said contact members are movable towards and from each other for controlling the flow of current in an electrical circuit, said mounting means causing a wiping action between the contact members as they are moved into circuit closing position, at least one of said contact members comprising a finely divided metallic compound 55 sintered with a metal binder which, when current passes through said contact member, melts sufficiently to release particles of the finely divided metallic compound at the point of contact and 60 leave minute craters in the surface of the contact member thereby to cause the member to have and retain a hard, rough contact surface in operation, said rough contact surface and said wiping action causing frictional effects to damp 65

the vibrations of said contact members and prevent contact bounce.

2. A relay comprising a plurality of contacts for controlling the flow of current in an electrical circuit, said contacts comprising tungsten carbide sintered with a metal binder which, when the current passes through said contacts, melts sufficiently to release particles of the tungsten carbide and cause the contacts to have and retain hard, rough faces in operation, and means including yieldable supports for said contacts having substantially the same period of vibration, said contacts and supports coating, when the contacts are brought into electrical engagement with one another, to cause movement of the contacts relative to each other in such time relation as to prevent separation of the contacts during said movement and to bring the contacts quickly to rest by reason of the friction between the rough surfaces thereof.

3. A relay structure including resilient contact mounting means, a pair of metallic contacts supported by said means for controlling the flow of current in an electrical circuit, said contacts comprising tungsten carbide sintered with a metal binder which, when the current passes through said contacts, melts sufficiently to release particles of the tungsten carbide and cause the contacts to have and retain rough contact faces in operation, said rough contact faces co-acting to prevent any phase difference in the frequencies of the resilient mounting means from causing a momentary separation of said contacts as the relay is operated to circuit closing position.

4. An electrical contact structure including a plurality of metallic contact elements for controlling the flow of current in an electrical circuit, said contacts comprising tungsten carbide sintered with a metal binder which, when the current passes through said contacts, melts sufficiently to release particles of the tungsten carbide and cause the contacts to have and retain hard, rough faces in operation, a resilient mounting for each of said contact elements, said mountings having substantially the same frequency, and means including said hard rough faces and said mountings for causing the contact elements to remain in continuous contact during the operating period of said elements.

5. An electrical contact structure comprising a plurality of complementary metallic contact members, at least one of which members comprising tungsten carbide sintered with a metal binder which, when the current passes through said member, melts sufficiently to release particles of the tungsten carbide and cause the member to have and retain a hard, rough contact surface in operation, and mounting means whereby one of said contacts is movable relative to the other, said mounting means causing a wiping action between the contacts as the contacts are brought into circuit closing position, said rough contact surface and said wiping action causing frictional effects to damp the vibrations of said contact members and prevent contact bounce.

JOHN A. HERBST.
